UNITED STATES PATENT OFFICE

1,996,397

TOP RACK LIGHTER

Eugene L. Baker, Taunton, Mass.

Application August 8, 1932, Serial No. 627,977

2 Claims. (Cl. 158—115)

This invention relates to gas stove tops, and aims to provide a gas stove top having means for directing the gas and air mixture from a gas burner, to a pilot flame igniting gas burners disposed under the top.

The inner ends of the conduits are disposed at the center of the stove top where they communicate with an opening 8 directly over the pilot burner 9, so that the gas will fill the conduits and become ignited by the pilot burner, lighting the gas at the main burner.

In the form of the invention as shown by Figure 6 of the drawings, the stove top rack is formed with passageways 10 that have inclined side walls over which the upstanding flanges 11 slide, the 10 flanges 11 being formed integral with the plate 12 that forms the bottom of the conduit.

As shown by Figure 8 of the drawings the stove top is provided with integral supporting rings 13 that are spaced apart under the top of the stove 15, accommodating the removable conduits 14 that have downwardly extended end portions 15 disposed directly over the burners.

Thus it will be seen that due to this construction, the conduits may be adjusted for use in connection with stove tops of various sizes.

Set screws 16 are provided, and as shown extend through the rings supporting the conduits, thereby holding the conduits in their positions of adjustment.

In the form of the invention as shown by Sheet 3 of the drawings, conduits indicated by the reference character 17 are formed integral with the stove top sections and as shown, extend laterally to where the open outer ends thereof overlie the burners 18 of the gas stove. Openings 19 are formed directly over the pilot burner 20, and provide means to carry off some of the products of combustion, incident to the burning of the pilot burner.

As clearly shown by Figure 12, the conduits 17 have their lower sides open, so that a certain amount of air may mix with the gas, to aid combustion.

From the foregoing it will be seen that when the gas burner is to be lighted, the usual valve is opened, allowing gas to collect in the conduits. The pilot will ignite the gas in the conduits, resulting in the blaze lighting the burners.

I claim:

1. The combination in a gas stove, of a series of main burners and a pilot burner, a stove top for the stove, spaced fingers forming channels, disposed on the lower surface of the stove top and extending from the pilot burner to the main burners, spaced supporting rings connecting the flanges of the channels, tubular conduits within the channels and held within the supporting rings, means for adjustably securing the tubular conduits within the channels, the inner ends of

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a burner constructed in accordance with the invention.

Figure 2 is a sectional view taken on line 2—2 of Figure 1.

Figure 3 is a fragmental bottom plan view of the stove top rack.

Figure 4 is a longitudinal sectional view through one of the conduits leading from a pilot burner.

Figure 5 is a sectional view taken on line 5—5 of Figure 4.

Figure 6 is a longitudinal sectional view through a modified form of conduit.

Figure 7 is a sectional view taken on line 7—7 of Figure 6.

Figure 8 is a further modified form of the invention, illustrating a removable conduit.

Figure 9 is a sectional view taken on line 9—9 of Figure 8.

Figure 10 is a plan view of a modified form of the invention.

Figure 11 is a longitudinal sectional view through the modified burner lighter.

Figure 12 is a sectional view taken on line 12—12 of Figure 11.

Referring to the drawings in detail, the stove top is indicated generally by the reference character 5 and embodies the usual separable sections.

Formed integral with the stove top rack sections, are conduits indicated by the reference character 6, which conduits have downwardly extended end portions 7 disposed adjacent to the burners of the stove, so that a flame will be directed to the burners.

the tubular conduits communicating with the channels so that gas passing through the conduits may be ignited at the pilot burner, and the outer ends of the tubular conduits extending downwardly to positions adjacent to the main burners.

5. 2. The combination in a gas stove, of a series of main burners and a pilot burner, a stove top

for the stove, spaced fingers embodying channels having their open sides disposed downwardly arranged on the under surface of the stove top, and a movable member cooperating with each channel member and providing a gas passageway between the pilot burner and one of the main burners.

EUGENE L. BAKER.
